TICKET ISSUING DEVICE

Etienne M. Boegner, New York, N. Y.

Application December 8, 1944, Serial No. 567,271

15 Claims. (Cl. 164—48)

1

This invention relates to devices for issuing tickets, sales slips, and the like, and it relates particularly to a ticket issuing device capable of issuing one or more tickets, respectively, in response to the actuation of selective control buttons or keys.

An object of the present invention is to provide a simplified electrically operated ticket issuing device.

Another object of the invention is to provide an electrically operated ticket issuing device of simplified form which is capable of issuing one or more tickets upon actuation of the control buttons or keys thereof.

A further object of the invention is to provide a ticket issuing device which does not contain clutches and complicated actuation mechanisms for issuing predetermined numbers of tickets in strip form.

Other objects of the invention will become apparent from the following description of a typical form of ticket issuing device embodying the present invention.

In accordance with the present invention, I have provided a ticket issuing mechanism which includes an oscillatable element for engaging and advancing a ticket strip in one direction of movement and disengaging and moving relatively to the strip upon return movement. More particularly, the device includes a guide for the ticket strip which is adapted to be moved toward and away from the oscillatable member to engage or disengage the member and a strip of tickets so that the feeding of the strip takes place in only one direction of movement of the oscillatable member.

The device is also provided with a shearing mechanism for severing the strip of tickets after a desired number of tickets has been advanced by the oscillatable member.

The various cooperating elements preferably are actuated by means of suitable solenoids and through simple mechanical connections whereby the actuation of the guide, the oscillatable ticket advancing member, and the cut-off means take place in sequence.

Inasmuch as the armatures of the solenoids reciprocate, a simplified mechanism for controlling the motion of the ticket advancing mechanism is provided. This control member may consist of a bar-like element fixed to the armature and having a plurality of spaced apart projections thereupon which are adapted to engage stop members actuated by the control keys. The stop members are spaced apart such dis-

2

tances that the movement of the bar is proportional to the number of tickets to be issued. Thus, the spacing between a projection and one stop member may be such that the bar will move a distance proportional to the length of one ticket before the projection and the stop member engage. Other stop members and projections are so located that the bar travels a greater distance, and, therefore, more than one ticket may be issued before the stop member and the projection come into engagement.

The device is provided with means responsive to the motion of the ticket advancing means which automatically cuts off the current supply to the solenoids when the desired number of tickets has been advanced, and mechanism for restoring the ticket advancing means to its initial position ready for the issuance of additional tickets.

Ticket issuing devices of the type described above are compact and can be duplicated easily. For these reasons, any desired number of such ticket issuing devices may be assembled in a suitable case to permit the issuance of tickets of differing value.

For a better understanding of the present invention, reference may be had to the accompanying drawings in which:

Figure 1 is a view in vertical section of a typical form of ticket issuing device embodying the present invention;

Figure 2 is a view in section and partly broken away taken on line 2—2 of Figure 1;

Figure 3 is a view in section taken on line 3—3 of Figure 1;

Figure 4 is a schematic diagram of the electrical circuit for the device; and

Figure 5 is a schematic diagram of a modified electrical circuit for the device.

The form of ticket issuing device chosen to illustrate the present invention may consist of a casing 10 formed of sheet metal or any other desired material having a bottom 10a, a front wall 10b, a back wall 10c, a top 10d, and side walls 10e. The casing 10 is formed with a rearwardly projecting compartment 11 for receiving the control keys 12a to 12e of the device and the associated control mechanism.

Near the forward end of the top surface 10d is a slot 13 provided with a lightweight hinged door 14 through which the tickets in the form of a strip 15 are projected.

The ticket strip 15 is an elongated strip of relatively stiff cardboard having a plurality of equally spaced perforations.

The mechanism for issuing the tickets includes a shiftable, arcuate tubular guide member 16 having a slot 16a in its under surface in order to expose the portion of the strip 15 having the perforations therein. The guide member 16 is provided with a journal 16b on its upper surface in which is rotatably received a pivot pin 17 on a ball crank lever 18. The receiver 18 is pivotally supported by means of a pivot pin 19 projecting from a partition or the wall 10e of the casing 10 and has its lower arm 18e connected by means of a link 20 to a reciprocating knife or shear blade 21. The shear blade 21 is rigidly supported upon the end of a rod or shaft 22 that is slidably guided in a bearing member 23 fixed to the under surface of the top 10d adjacent the opening 13. The blade 21 is normally urged to the left as viewed in Figure 1 by means of a spring 24 mounted on the shaft 22. The blade 21 cooperates with a second shear blade 25 which is fixed to the top 10d adjacent the opening 13 so that the ticket strip 15 must pass between the shear blades 21 and 25 in order to pass through the opening 13.

The shear blade 21 is reciprocated toward and away from the blade 25, and the guide member 16 is raised and lowered by means of a quick-response solenoid 26 having a reciprocable armature member 27 that is connected by means of the lever 28 to the shear blade 21. The lever 28 may be pivotally supported by means of a pivot pin 29 fixed to the casing partition 10e. Thus upon movement of the armature 27 to the left as viewed in Figure 1, the shear blade 21 is moved toward the right and the guide member 16 is rocked downwardly by means of the bell crank member 28.

The strip of tickets 15 may be fed from a supply hopper 30 mounted in the bottom of the case and is directed upwardly through another fixed arcuate guide member 31 into the lower end of the guide member 16.

The strip 15 is advanced by means of an oscillatable sector shaped member 32 which is pivotally supported in the casing 10 by means of a shaft 33 projecting from the partition 10e. The sector member 32 may consist of a metal stamping having a flange 32a extending at substantially a right angle to the body of the member 32 as shown in Figure 2, and a tubular hub 32b for receiving the shaft 33. The flange 32a is provided with a plurality of projections or pins 32c which are spaced at such intervals as to engage the perforations in the ticket strip 15.

When the pins 32c are engaged in the perforations 15a, and the member 32 is rotated clockwise, the ticket strip is advanced to the right. In order to produce such movement of the sector member 32, the hub 32b has attached thereto a lever 34 having a pin thereon which engages in an elongated slot 35a in a lever 35 that is pivotally supported by means of a pivot pin 36 on the casing 10 of the device. The lever 35 is provided with a pivot pin 37 which is connected with the reciprocating armature 38 of a slow-response solenoid 39. Thus upon movement of the armature 38 to the left as viewed in Figure 1, the lever 35 is moved clockwise and the sector 32 is also moved clockwise but through a greater angular distance. The movement of the armature 38 may be at least sufficient to cause a 90° movement of the sector 32 from the position disclosed in Figure 1. The sector member 32 may be returned to the position shown in Figure 1, by means of a spring 40 that is connected to the

lever arm 35 and a portion of the front wall of the casing 10 as shown in Figure 1.

If desired, the hub 32b may be connected to a counter 42 of conventional type by means of a flexible shaft coupling 43 and an overrunning clutch (not shown) in order to indicate the total number of tickets issued by the device.

In order to control the device so that any number of tickets from one to five, for example, may be issued, the armature of the solenoid 39 is provided with a rearwardly extending bar or shaft 45 which is provided, as shown, with five spaced apart projections 45a, 45b, 45c, 45d, and 45e. These stop members 45a to 45e co-operate selectively with five stop members 46, each of which is under the control of one of the keys 12a to 12e. Inasmuch as the stop members 46 are identical, only one of these members will be described herein.

Each stop member 46 includes a lever arm 46a (Figure 3) which is pivotally supported upon a shaft 47 extending longitudinally of the casing and supported by the partition 10e. The member 46 also includes a laterally projecting lever arm 46b which is engaged by the spindle or push rod 48a to 48e extending downwardly from each key 12a to 12e. The stop member 46 is normally urged in a clockwise direction as viewed in Figure 3 by means of a coil spring 49 engaging the lever arm 46b. The spring 49 biases the lever arm clockwise away from the bar 45 and the projection 45e as shown in Figure 3 so as to prevent engagement between the projection 45e and a pawl member 50 (Figure 1) pivotally mounted on the upper end of the member 46.

When the key 12a is depressed, for example, the corresponding member 46 is rocked in a counter-clockwise direction as viewed in Figure 3 in order to bring the downwardly projecting tooth 50a into alignment with the projection 45e on the bar 45, thereby limiting the rocking movement of the sector member 32 to an angular distance sufficient to issue five tickets.

If the next adjacent key 12b which controls the issuance of four tickets is depressed, the member 46 corresponding to the projection 45d is rocked into position to intercept the projection 45d and thus permit the bar 45 to travel only four-fifths as far as the distance when projection 45e is used as the stop, whereby only four tickets will be issued.

Similarly, when the projection 45c, 45b, or 45a is used as a stop control, three, two, and one tickets, respectively, will be issued.

Referring now to Figures 1 and 4, the keys 12a to 12e are used to operate a switch member 53 by means of which the solenoids 26 and 39 are energized. The switch 53 may be of the micro-switch type having a plunger 53a extending therethrough which, upon depression, closes the switch and connects the solenoids 26 and 39 to a source of electric current by means of the conductors 54 and 55. A plate 56 rests upon the plunger 53a and is provided with a slot corresponding to each key 12a to 12e, which receives a reduced portion 48f on each of the spindles 48a to 48e. Thus when a key 12a, for example, is depressed, the actuating plate 56 is engaged by the spindle 48a and forced down, closing the switch 53 and energizing both of the solenoids 26 and 39, with the result that the shear blade 21 is quickly retracted to the right and the arcuate guide member 16 is moved toward the sector member 32. The pins 32c are engaged by the perforations of the ticket strip and the sector 32

is rocked clockwise until one of the projections 45a to 45e engages its corresponding stop member 46. When this occurs, the corresponding pawl member 50 is rocked clockwise and engages a plate 57 which is supported above the stop member and lifts this plate. As the plate 57 is lifted, the plunger 53a is moved upwardly, opening the switch 53a and deenergizing the solenoids, and the actuating plate 56 is also lifted by means of a rotary cam lever 57a (Figure 1) supported on the partition 10e, with the result that the keys 12a to 12e cannot actuate the switch 53a until the sector member 32 is restored to its initial position. When the current supply to the solenoids 26 and 28 is shut off, the shear blade 21 is immediately urged to the left by means of the spring 24, shearing off the tickets that have been projected through the opening 13 and lifting the guide 16. Also the spring 40 causes the sector 32 to rock in a counterclockwise direction restoring it to the position disclosed in Figure 1 and, of course, restoring the entire mechanism to its initial position.

The device may be equipped with a mechanism for indicating when all but five of the tickets in the strip have been issued. This mechanism includes a bell crank lever 58 pivotally supported on the lower end of the guide member 31 and having a roller 58a on one arm thereof bearing against the ticket strip 15. The other arm 58b is provided with a plunger 59 which bears against the undersurface of the plate 57 and the entire bell crank 58 is normally urged in a counterclockwise direction by means of a spring 60. Thus when the free end of the ticket strip passes the roller 58a, the bell crank lever will rotate in a counterclockwise direction, thereby lifting the plates 57 and 56 and shutting off the current to the solenoids. A manual control lever or handle 58c may be provided on the bell crank 58 for rocking the bell crank back to its normal position, thereby permitting the last five tickets to be issued.

The mechanism described above is simple, can be formed of a relatively few parts as compared with prior ticket issuing devices, while at the same time affording great flexibility and ease of control in the issuing of tickets. A plurality of ticket issuing devices of the type described above can be combined in a single case 10 so that a variety of tickets of different values can be issued automatically. It will be understood that the number of keys and that the number of tickets that can be issued by the actuation of a single key can be varied widely. Thus the devices can be modified to permit it to issue six tickets or more by depressing an appropriate key, or it may be provided with only one or two keys for issuing one or two tickets. Moreover, the electrical system for actuating the solenoids successively may be modified to include a separate switch 69 for controlling the solenoid 39, as shown in Figure 5. This switch 69 is closed by the armature of the solenoid 26 when the latter is energized to energize the solenoid 39 under the control of the switch 53 to move the guide 16 toward the sector member 32 before the latter is moved. The slow acting solenoid 39 permits the guide 16 to move away from the sector member 32 before the latter returns to its initial position.

Therefore, it will be understood that the ticket issuing devices of the type embodying the present invention are susceptible to considerable modification and the above described embodiment of the invention accordingly should be considered

as illustrative and not as limiting the scope of the following claims.

I claim:

1. A ticket issuing device comprising an arcuate tubular guide for receiving a strip of tickets having perforations therein, an oscillatable sector member adjacent to said guide and having projections thereon for entering said perforations, means supporting said guide for movement toward and away from said sector member to engage and disengage said projections and perforations, an electrical means for rocking said sector in one direction to advance said strip through said guide, another electrical means for moving said guide toward said sector, and manually operable means for actuating both of said electrical means for moving said guide toward said sector and thereafter rocking said sector in said one direction to advance tickets through said guide.
2. A ticket issuing device comprising an arcuate tubular guide for receiving a strip of tickets having perforations therein, an oscillatable sector member adjacent to said guide and having projections thereon for entering said perforations, means supporting said guide for movement toward and away from said sector member to engage and disengage said projections and perforations, an electrical means for rocking said sector in one direction to advance said strip through said guide, another electrical means for moving said guide toward said sector, and manually operable means for actuating both of said electrical means for moving said guide toward said sector and thereafter rocking said sector in said one direction to advance tickets through said guide, and means for moving said guide away from said sector to disengage said projections from said perforations after said sector has been rocked in said one direction.
3. A ticket issuing device comprising an arcuate tubular guide for receiving a strip of tickets having perforations therein, an oscillatable sector member adjacent to said guide and having projections thereon for entering said perforations, means supporting said guide for movement toward and away from said sector member to engage and disengage said projections and perforations, an electrical means for rocking said sector in one direction to advance said strip through said guide, another electrical means for moving said guide toward said sector, shearing means connected with said another electrical means for severing said strip and opened by said another electrical means as said guide is moved toward said sector member, and manually operable means for actuating both of said electrical means for moving said guide toward said sector and thereafter rocking said sector in said one direction to advance tickets through said guide, and means for moving said guide away from said sector to disengage said projections from said perforations and closing said shearing means to sever said strip after said sector has been rocked in said one direction.

4. A ticket issuing device comprising a tubular guide for receiving a strip of tickets having holes therein, said guide having a longitudinal slot exposing a portion of the strip and the holes therein, a sector member having projections thereon adapted to enter said holes, means supporting said guide for movement toward and away from said sector member to engage and disengage said projections and said holes, shearing means adjacent to one end of said guide

having relatively movable blades, means connecting said shearing means and said guide for opening said blades when said guide moves toward said sector member, and closing said blades as said guide moves away from said sector member, means for oscillating said sector, means for moving said guide toward and away from said sector, and manually operable means for controlling said sector oscillating and said guide moving means to advance said tickets along said guide and shear tickets from said strip.

5. A ticket issuing device comprising a movable guide for a strip of perforated tickets, an oscillatable member adjacent to said guide for advancing said strip along said guide, means supporting said guide for movement toward and away from said member, shearing means including relatively movable blades adjacent to one end of said guide, solenoid means connected to said shearing means and said guide for opening said blades and moving said guide toward said member, solenoid means for rocking said member from an initial position to advance said strip, means for closing said shearing means and moving said guide away from said member and thereafter rocking said member back to said initial position, and manually operable means for energizing said solenoids and controlling the movement of said member to advance a predetermined number of tickets along said guide and sever them from said strip.

6. A ticket issuing device comprising a guide for a strip of perforated tickets, an oscillatable member having projections for engaging the perforations to advance the strip, a solenoid for moving said guide toward said member, means for moving said guide away from said member, a solenoid for rocking said member in a direction to advance said strip along said guide, and manually operable means for energizing said solenoids to move said guide toward said member to engage said projections in said perforations and thereafter rock said member to advance said strip.

7. A ticket issuing device comprising a guide for a strip of perforated tickets, an oscillatable member having projections for engaging the perforations to advance the strip, a solenoid for moving said guide toward said member, means for moving said guide away from said member, a solenoid for rocking said member in a direction to advance said strip along said guide, and manually operable means for energizing said solenoids to move said guide toward said member to engage said projections in said perforations and rock said member to advance said strip, and means responsive to movement of said member for deenergizing said solenoids.

8. A ticket issuing device comprising a guide for a strip of perforated tickets, an oscillatable member having projections for engaging the perforations to advance the strip, a solenoid for moving said guide toward said member, means for moving said guide away from said member, a solenoid for rocking said member in a direction to advance said strip along said guide, a plurality of keys, switch means actuated by said keys for energizing said solenoids, an elongated member having a plurality of spaced apart projections thereon connected to and movable with said oscillatable member, and stop members movable relatively to said elongated member into the paths of said spaced apart projections to limit the movement of said oscillatable member, each

10 of said stop members being actuated by a different key.

9. A ticket issuing machine comprising a guide for a strip of tickets, a reciprocating strip feeding member arranged adjacent said guide for engaging a strip of tickets on said guide and for advancing the same, means supporting said guide for relative movement toward and away from said feeding member for effecting a driving engagement between said feeding member and a strip of tickets on said guide, means for controlling the extent of forward movement of said feeding member to control the distance through which said strip is advanced, means for 15 moving said supporting guide away from said feeding member to disengage the latter from said strip at the completion of said forward movement of said feeding member and for returning said feeding member to its home position, and means for severing said strip upon completion of said forward movement.

10. A ticket issuing device comprising a guide for a strip of perforated tickets, an oscillatable member, means movable with said member for engaging in said perforations to advance said strip in one direction of oscillation of said oscillatable member, a solenoid for rocking said oscillatable member in a direction to advance said strip when said solenoid is energized, a plurality 20 of movable keys, switch means actuated by movement of each of said keys for energizing said solenoid, an elongated control member connected, and movable, with said oscillatable member, and separate elements, each actuated by a different one 25 of said keys, movable toward said control member in response to actuation of their respective keys, means movable with said control member for engaging one of said elements corresponding to an actuated key to displace said element, and means responsive to displacement of said element for opening said switch means to deenergize said solenoid.

11. A ticket issuing device comprising a guide for a perforated strip of tickets, cutting means 25 including a movable blade for severing said strip, a first solenoid for withdrawing said blade when said solenoid is energized, means for urging said blade in a direction to sever said strip, an oscillatable member, a second solenoid for rocking 30 said member in one direction when said solenoid is energized, means urging said oscillatable member in the opposite direction, means movable with said oscillatable member for engaging said strip and advancing it through said cutting means when said second solenoid is energized, a plurality 35 of depressible keys, each key corresponding to a different number of tickets to be severed from said strip, switch means movable to closed position to energize said first and second solenoids upon depressing each of said keys, separate stop control elements corresponding to each key displaceable from one position to a second position upon depressing of a corresponding key, an elongated control member connected 40 to said oscillatable member and movable relatively to said stop control elements upon movement of said oscillatable member, and means movable with said control member for engaging and displacing a stop control element when the latter is in said second position, and means responsive to displacement of said control element for opening said switch means to deenergize said first and second solenoids.

12. A ticket issuing device comprising a guide 45 for a perforated strip of tickets, cutting means in-

cluding a movable blade for severing said strip, a first electrically actuated means for withdrawing said blade when said electrically actuated means is energized, means for urging said blade in a direction to sever said strip, an oscillatable member, a second electrically actuated means for rocking said member in one direction when said second electrically actuated means is energized, means urging said oscillatable member in the opposite direction, means movable with said oscillatable member for engaging said strip and advancing it through said cutting means when said second electrically actuated means is energized, a plurality of depressible keys, each key corresponding to a different number of tickets to be severed from said strip, switch means movable to closed position to energize said first and second electrically actuated means upon depressing each of said keys, separate control elements corresponding to each key, each control element being movable from one position to a second position upon depressing of a corresponding key, an elongated control member connected to said oscillatable member and movable relatively to said control elements upon movement of said oscillatable member, and means movable with said control member for engaging and displacing a control element when the latter is in said second position, and means responsive to displacement of said control element for opening said switch means to deenergize said first and second electrically actuated means.

13. A ticket issuing device comprising a guide for a strip of perforated tickets, an oscillatable member having projections for engaging the perforations to advance the strip, a first solenoid having a movable armature connected to said guide for moving said guide toward said member, means for moving said guide away from said member, a second solenoid for rocking said member in a direction to advance said strip along said guide, manually operable means for energizing said first solenoid to move said armature and thereby move said guide toward said member to engage said projections in said perforations, and switch means actuated by movement of said armature to energize said second solenoid to rock said member to advance said strip.

14. A ticket issuing device comprising an ar-
cuate guide member for receiving a perforated ticket strip, cutting means including a movable blade adjacent to one end of said guide member, a first solenoid for withdrawing said blade when said solenoid is energized, means for urging said blade in a direction to sever said strip, an oscillatable member substantially concentric with said guide member, a second solenoid for rocking said member toward said cutting means, means urging

said oscillatable member in the opposite direction, means on said oscillatable member for engaging said strip and advancing it through said cutting means when said second solenoid is energized, a plurality of depressible keys, each key corresponding to a different number of tickets to be severed from said strip, first switch means actuated to energize said first solenoid to withdraw said blade upon depressing any of said keys, second switch means responsive to withdrawal of said blade to energize said second solenoid to rock said oscillatable member toward said cutting means, an elongated control member reciprocable in response to rocking of said oscillatable member, and a plurality of stop control elements spaced apart lengthwise of said control member and movable, by depressing said keys, into the path of said control member for engagement thereby to actuate said first switch to limit the movement of said oscillatable member to an amount substantially equal to the length of the ticket strip containing the number of tickets corresponding to the key depressed.

15. A ticket issuing device comprising a guide for a strip of perforated tickets, an oscillatable member having at least one projection for engaging said perforations to advance said strip, a cutting means adjacent one end of said guide and including a movable blade for severing said strip, a solenoid having a movable armature, means connecting said armature to said blade for withdrawing said blade when said solenoid is energized, means urging said blade in the opposite direction to sever said strip, a second solenoid for rocking said oscillatable member in a direction to advance said strip through said guide and cutting means, means for rocking said oscillatable member in the opposite direction, and a switch for energizing said solenoid to advance said strip, said switch being actuated to energize said second solenoid by movement of said armature when said first solenoid is energized.
